PARTITION FOR SINKS

Frederick A. Hanson, Los Angeles, Calif.

Application March 11, 1939, Serial No. 261,244

7 Claims. (Cl. 4—183)

This invention relates to means for effecting a fluid-tight connection between the edge and face of two walls disposed transversely to each other, and while the invention may be used for this general purpose in other situations, in the present specifications it is described as applied to a transverse wall or partition to be set up in a tub or sink.

Modern kitchen sinks are now frequently constructed with a fixed wall that divides the sink into two sections. This is very convenient in washing dishes because a rinsing bath may be maintained on one side of the partition and the washing bath and suds on the other side.

Such a partition or dam wall has been suggested heretofore, provided with vacuum cups to seat against the bottom or wall of the sink to hold the dividing wall in place, but my experiments along this line have demonstrated that merely providing the wall with vacuum cups to seat against the sink bottom is insufficient to prevent leakage into the cup and to effect a good serviceable attachment between the lower edge of the division wall and the sink.

One of the objects of this invention is to overcome this difficulty and to provide means co-operating with the cup in such a way as to insure the maintenance of substantially perfect vacuum within the cup, thereby insuring high pressure and a tight seal around its edges.

A further object of the invention is to provide a division wall with means for supporting it on the cup in such a way that in setting the wall in place a force is exerted from the middle of the cup wall to keep pressing the lower edge of the plate against the face to which it is sealing.

It has been proposed heretofore to hold a division wall of this kind in place by means of a vacuum strip extending along near the lower edge of the wall but that type of connection seems objectionable because the slightest imperfection of the seal at any point along its length will "break" the vacuum for the entire length of the strip, and accordingly one of the objects of the present invention is to provide an apron type of seal that will overcome this objection.

A further object of the invention is to provide simple means for enabling drainage to be effected at the lower edge of the wall when desired. This makes it unnecessary to remove the division wall every time it is used, in order to drain the sink.

Further objects of the invention will appear hereinafter.

The invention consists in the novel parts and combination of parts to be described hereinafter, all of which contribute to produce an efficient partition for sinks.

A preferred embodiment of the invention is described in the following specification, while the broad scope of the invention is pointed out in the appended claims.

In the drawing:

Fig. 1 is a vertical cross-section through a sink 10 illustrating a dividing wall embodying my invention, in place and ready to be seated there.

Fig. 2 is a vertical section upon a larger scale on the line 2—2 of Fig. 1, passing through the sink bottom, and further illustrating details of 15 one embodiment of the invention.

Fig. 3 is a view similar to Fig. 2 but illustrating another embodiment of the invention, which I call the apron type.

Fig. 4 is a section on the line 4—4 of Fig. 3, 20 showing part of the side wall of the sink, further illustrating the construction of this apron type of the invention.

Fig. 5 is a horizontal section of a division wall showing a portion of the bottom section of the 25 gasket and particularly illustrating a gate that may be provided for draining through the division wall. In dotted lines the gate is illustrated in its open position.

Fig. 6 is a vertical section about on the line 30 6—6 of Fig. 5, passing through the lower edge of the division wall and the gasket and also passing through the adjacent portion of the sink bottom.

In the embodiment illustrated in Figs. 1 and 2, 35 the wall to be sealed is in the form of a plate 1 fitting approximately to the cross-section of the sink 2 and provided on its edge with a gasket 3. This gasket may extend only on the bottom and side edges of the plate, but if desired may be 40 in the form of a continuous strip of cushion material such as rubber, the ends of which are brought together and secured by means of a saddle clip 4 attached to the upper edge of the plate. This gasket is thick enough to insure 45 that the division plate 1 can be made watertight in sinks with inclined walls and that may vary in inclination. Another function performed by the gasket is to develop a resistance to the seating of the partition and develop a force acting 50 in a direction to maintain an upward pull on the middle of each vacuum cup 5.

There may be as many of these cups as desired but in Figs. 1 and 2 I have illustrated only two, one on each side. Each cup is secured in place 55

by means of a bracket 6 secured to the plate 1 and having a substantially horizontal arm attached to the middle of the cup by means of a threaded shank 7. These brackets may be rigid but are preferably of resilient material such as spring steel.

The gasket may be a pneumatic tube but as illustrated, it is of solid rubber preferably formed with a V-shaped or U-shaped notch 8 in its outer 10 face, thereby forming two projecting lips 9 that press against the inner surface of the sink and make a tight seal all around the plate.

In seating the plate the pressure of the brackets on the cups, flattens them down against the 15 bottom and also compresses the gasket. The resiliency of the rubber gasket tends to push it up and also pull up the cups. These forces balance each other, the upward push of the gasket maintaining the vacuum in the cups. The resiliency 20 of the brackets gives a "follow up" to this action.

In order to enable the retained water to be drained, I prefer to provide a movable gate 19. This gate is preferably an integral part of the gasket, having a cross-section such as shown in 25 Fig. 6, and swings open as indicated by the dotted lines in Fig. 5. The free edge of the gate is cut on a bevel or incline so as to fit against a correspondingly beveled seat 11. This bevel insures substantial tightness of the gate. The gate 30 will hold itself open or closed on account of the compression of the gasket, but means such as a small vacuum cup 12 may be attached to the gate to hold it open. This would be accomplished by pressing down on the cup 12 while the 35 gate is in its open position.

In the embodiment shown in Figs. 3 and 4 the body of the gasket 13 does not seat against the surface of the sink but is provided with a laterally extending apron 14 that lies against the 40 surface of the sink, and is preferably provided with a series of cups formed in the material of the apron. When the partition is put in place these cups should be pressed down flat in succession by one's hand, and operate to adhere to the sink surface. This apron extends continuously across the bottom of the sink and up its sides.

The other side of the partition 16 should be provided with one or more vacuum cups such as 50 the cup 17 for securing the partition itself to the sink bottom.

As the cups 15 are distinct from each other it is evident that a leak at one cup will be confined to that cup and the remaining cups will continue to function.

Many other embodiments of this invention may be resorted to without departing from the spirit of the invention.

What I claim is:

60 1. A removable sink partition having a body of a form approximating the inner cross-section of the sink, compressible sealing means for effecting a substantially water-tight seal for the edge of the body adjacent the surface of the sink, a bracket attached to the body and projecting laterally therefrom, and a vacuum cup carried by said bracket for engaging and clinging to the said surface, said bracket, after the cup has been pressed forcibly toward the surface, operating to 65 impart force to the partition to press the sealing means against the surface.

2. In a removable sink partition having a body with a form approximating the inner cross-section of the sink, a substantially water-tight compressible gasket on the edge of the body, a yield-

ing spring-form bracket attached to the body and projecting laterally therefrom, and a vacuum cup carried by said bracket for engaging, and clinging to, the inner face of the sink body.

3. A removable sink partition having a body 5 with a form approximating the inner cross-section of the sink, compressible gasket means for effecting a substantially water-tight seal for the edge of the body adjacent the surface of the sink and for exerting an upward thrust on the 10 said body when the partition has been forced down into place, a resilient bracket attached to the body and projecting laterally therefrom, a vacuum cup carried by said bracket to be forced against the sink surface so as to cling to the inner face of the sink body, said gasket means and said resilient bracket cooperating with the vacuum cup to maintain the body securely in position.

4. A removable sink partition having a rigid 20 body with a form approximating the inner cross-section of the sink, compressible sealing means between the edge of the body and the sink wall for effecting a substantially water-tight seal for the edge of the body, a spring-form bracket attached to the body and projecting laterally therefrom, a vacuum cup carried by said bracket to be pressed against, and clinging to, the inner face of the sink body, said spring bracket and vacuum cup cooperating to maintain the partition in 25 a substantially vertical plane and with the sealing means forcibly pressed against the sink bottom.

5. A removable sink partition having a rigid body with a form approximating the inner cross-section of the sink, compressible sealing means between the edge of the body and the sink wall for effecting a substantially water-tight seal for the edge of the body, a spring-form bracket attached to the body and projecting laterally therefrom, a vacuum cup carried by said bracket to be pressed against, and clinging to, the inner face of the sink body, said spring bracket and vacuum cup cooperating to maintain the partition in 30 a substantially vertical plane and with the sealing means forcibly pressed against the sink bottom.

6. A removable sink partition having a body with a form approximating the inner cross-section of the sink, a vacuum cup attached to the body for securing the same to the bottom, and 35 an apron of flexible material extending along the edge of said body and having a plurality of non-communicating vacuum cups formed as cup-form recesses the walls of which merge into the wall of said apron, for engaging the inner surface 45 of the sink to secure the apron thereto.

7. A removable sink partition having a rigid plate-form body approximating in outline the inner cross-section of the sink, a compressible gasket attached to the edge of said body and located between the edge of the body and the surface of the sink when the partition is in place, vacuum cup means disposed on each side of the body and connected with the body, said vacuum cup means operating when pressed downwardly 65 against the bottom of the sink to exert a constant force maintaining the compressible sealing means in compression and holding the said body in a substantially vertical plane.
